H. V. RAU

FUSE PLUG

Filed Nov. 18, 1920

Harry V. Rau Inventor
By his Attorney
Frank D. Kent

UNITED STATES PATENT OFFICE.

HENRY V. RAU, OF BROOKLYN, NEW YORK, ASSIGNOR TO EDWIN B. STIMPSON COMPANY, OF BROOKLYN, NEW YORK.

FUSE PLUG.

Application filed November 18, 1920. Serial No. 424,993.

To all whom it may concern:

Be it known that I, HENRY V. RAU, a citizen of the United States, residing at Brooklyn, in the county of Kings and State of

5 New York, have invented certain new and useful Improvements in Fuse Plugs, of which the following is a specification.

This invention relates to improvements in fuse plugs and particularly to a novel 10 form of one of the two contact members between which the fuse element proper or wire extends.

The invention is particularly adapted to, and was designed for use in connection with, 15 a familiar type of fuse plug, which comprises a generally cup-shaped body of porcelain or other insulating material, with a contact piece extending through an aperture in the bottom of the cup, and a fuse element proper 20 or wire soldered to the contact piece and extending through an aperture in the side wall of the cup to a threaded contact shell which surrounds the cup circumferentially.

It has been the general practice to provide, as the contact piece which extends 25 through the bottom of the cup, a metallic piece which can be inserted in position, and which is more or less loosely held in position, one end of the fuse wire being soldered 30 to this contact piece. On account of the loose connection between this contact piece and the body of the plug the fuse wire, because it is fastened to the said contact piece and to the second contact piece on the out- 35 side of the body, is apt to be twisted or even broken when the plug is applied in use; and there are difficulties in connection with the soldering operation, as well as other objections to the use of devices heretofore known.

40 By my invention I provide a construction in which the contact piece, which extends through the bottom of the cup, is of such a form and character that it may be substantially immovably fixed in position and so 45 that the soldered connection between it and the inner end of the fuse wire may be readily made and secured against any tendency to loosen or to twist the fuse wire in the use of the device.

50 Other objects and aims of the invention, more or less broad than those stated above, together with the advantages inherent, will be in part obvious and in part specifically referred to in the course of the following 55 description of the elements, combinations,

arrangements of parts, and applications of principles constituting the invention; and the scope of protection contemplated will appear from the claims.

In the accompanying drawings, which are 60 to be taken as part of this specification, and in which I have shown merely a preferred form of embodiment of the invention,

Figure 1 is a vertical cross sectional view through a familiar type of fuse plug provided with my invention;

Figure 2 is a horizontal section on the line 2—2 of Figure 1 looking in the direction of the arrows;

Figure 3 is a bottom plan view of the 70 same;

Figure 4 is a central vertical sectional view through one of the contact members before it is placed in position in the plug;

Figure 5 is a view similar to Figure 1 75 illustrating a modification of the invention;

Figure 6 is a sectional view taken on the line 6—6 of Figure 5 looking in the direction of the arrows; and

Figure 7 is a bottom plan view of the 80 same.

Referring to the numerals on the drawings, there is shown at 8 a body of porcelain or other suitable insulating material having in general the shape of a cup, with 85 an aperture extending through the bottom thereof. In this aperture is to be inserted one of the contact members, such as illustrated in Figure 4, and indicated by the reference character 9. The contact piece 9 is 90 generally tubular, with a closed bottom 10 at one end, and with an outstanding flange 11 around its other and open end. The tubular member 9 is of a diameter to fit snugly the aperture in the bottom wall of the cup 95 8, and it is inserted into said aperture, with the flange 11 thereof resting either upon the outside of the bottom wall of the cup as in Figure 1, or on the inside of the bottom wall of the cup as in Figure 5. The tubular member 100 is of metal susceptible of being drawn or formed under pressure, and capable of assuming a permanent set when so drawn or formed. Assuming that the tube has been put in position in the bottom aperture of the cup, as suggested, it is firmly fixed in position by upsetting the closed end 105 of the tube and simultaneously dishing the closed end inwardly or towards the body of the tube to form a second outstanding flange 110

12 at the closed end of the tube, which will rest upon the inner side of the bottom wall of the cup (Figure 1), or against the outer side of the bottom wall of the cup (Figure 5), the metal being under stress, so that the bottom wall of the cup is firmly and immovably gripped between the flanges 11—12, which grip is maintained, because the metal takes a substantially permanent set.

10 In case the tubular contact piece has been positioned as in Figure 1, the dished closed end of the tube faces the interior of the cup 8 and provides a definite seat for one end of a fuse wire 14 and for a body of solder 15 whereby the end of the wire is electrically and mechanically united with the dished end of the tube. In case the tubular contact piece has been positioned as in Figure 5, the dished closed end of the tube is outside the bottom of the cup 8, and the open body of the tube, which is in communication with the interior of the cup 8, provides a seat for the end of the fuse wire and for the solder which connects the end of the fuse wire with the contact piece. The other end of the fuse wire passes out through an opening in the side wall of the cup and is held in a body of solder 16, which is in electrical and mechanical union with a surrounding screw shell 17. The open end of the cup may be covered with a mica window 18, held in position by a spun metal cap 19, as usual.

When the plug is in use, the flange 11 (Figure 1) or the flange 12 (Figure 5) as the case may be, forms one of the contacts for the fuse wire, while the shell 17 constitutes the other contact. Because of the substantially immovable fixation of the tubular contact piece, there is entire freedom

35 from relative movements of any of the parts, and particularly there is no possibility of the twisting of the fuse wire when the plug is turned down in its socket and friction occurs between the outwardly projecting flange 11 or 12 as the case may be, and the part with which it comes in contact. Furthermore, whichever way the tubular contact piece 9 is positioned, there is provided a definite seat for the end of the fuse wire

40 and for the solder which holds it in position, so that assembly is greatly facilitated and the danger of the solder working loose because of vibration or relative movement of parts, is minimized.

45 From one point of view the invention may be said to consist in providing for the apertured bottom wall of a fuse cup, a tubular metallic contact piece capable of being formed or drawn and of assuming a permanent set, closed at one end and with an outstanding flange around the other end, inserting the tube within the aperture with the flange resting against either the inside or the outside of the bottom wall, dishing

50 and upsetting the closed end of the tube to

form a second outstanding flange around the closed end of the tube and resting against the other side of the bottom wall of the cup, with the metal of the tube under stress and the two outstanding flanges gripping the bottom wall of the cup between them so that there can be no relative movement between the bottom of the cup and the tube without distortion or breakage of one or the other.

70 From another point of view, the invention may be said to consist of a fuse body or cup provided with an aperture in its bottom wall and a generally tubular contact piece passing through the aperture and having outstanding flanges contacting with the inner and outer surfaces of the bottom wall and gripping the same immovably between them, and a wall extending across the tube intermediate the said end flanges and constituting a definite seat for the end of a fuse wire and for solder.

80 Inasmuch as many changes could be made in the above construction, and many apparently widely different embodiments of my invention could be made without departing from the scope thereof, it is intended that all matter contained in the above description or shown in the accompanying drawings shall be interpreted as illustrative 95 and not in a limiting sense.

90 It is also to be understood that the language used in the following claims is intended to cover all the generic and specific features of the invention herein described 100 and all statements of the scope of the invention which, as a matter of language, might be said to fall therebetween.

I claim:—

1. In a device of the kind described, a 105 generally cup shaped body having an aperture through its bottom, a metallic tube having a wall extending thereacross intermediate the ends thereof and provided with outstanding flanges at both ends, the tube fitting the aperture of the body bottom with the outstanding flanges thereof resting upon opposite sides of the bottom wall and gripping the same immovably between them, substantially as set forth.

110 2. A device as set forth in claim 1, in which the closed end portion of the tube is dished towards the open end of the tube.

115 3. A device of the kind described comprising a cup shaped fuse body provided with an aperture in its bottom wall and a generally tubular contact piece passing through the aperture and having outstanding flanges contacting with the inner and outer surfaces of the bottom wall and gripping the same immovably between them, and a wall extending across the tube intermediate the said end flanges and constituting a definite seat for the end of a fuse wire 120 and for solder.

130

4. The method which consists in providing for the apertured bottom wall of a fuse cup, a tubular metallic contact piece capable of being formed and of assuming a permanent set, closed at one end and with an outstanding flange around the other end, inserting the tube within the aperture with the flange resting against one side of the bottom wall, dishing and upsetting the closed end of the 10 tube to form a second outstanding flange around the closed end of the tube and rest-

ing against the other side of the bottom wall of the cup, with the metal of the tube under stress and the two outstanding flanges gripping the bottom wall of the cup between them so that there can be no relative movement between the bottom of the cup and the tube without distortion of the tube or breakage of the cup. 15

In testimony whereof I affix my signature. 20

HENRY V. RAU.
